UNITED STATES PATENT OFFICE.

ARTHUR PAINTER, OF SAN FRANCISCO, CALIFORNIA.

CABLE-TRACTION SYSTEM.

SPECIFICATION forming part of Letters Patent No. 769,399, dated September 6, 1904.

Application filed July 24, 1903. Serial No. 166,901. (No model.)

To all whom it may concern:

Be it known that I, ARTHUR PAINTER, a citizen of the United States, residing at San Francisco, in the county of San Francisco and State 5 of California, have invented certain new and useful Improvements in Cable-Traction Systems, of which the following is a specification.

My invention relates to cable-traction systems in which buckets or receptacles are propelled from place to place by gripping an endless traveling rope.

My invention relates partly to an improved construction of grips for such receptacles, partly to means for letting go and taking the 15 rope by opening and closing such grips automatically, partly to means for handling and moving the receptacles or buckets at a terminal or other loading or discharging station while the grips are released, and also to improvements in features and details of construction and arrangement all tending to increased efficiency in this class of transportation.

I have illustrated a practical embodiment 25 of my invention in the accompanying drawings in connection with which this specification should be read.

Figure 1 is an elevation of the mechanism at a terminal or loading station in which my 30 improvements are included. Fig. 2 is a plan view of the same. Fig. 3 is an end elevation with the supporting-framework in cross-section. Fig. 4 is a longitudinal section of the grip closed. Fig. 5 is a similar section of the grip open. Fig. 6 is a bottom plan of the 35 grip in closed position with sliding jaw removed. Fig. 7 is a front elevation of the grip closed. Fig. 8 is a rear elevation of the same closed. Fig. 9 is a plan of the movable 40 jaw of the grip. Fig. 10 is a side elevation of both chains at their meeting-point.

Figs. 1, 2, and 3 represent arrangements at a loading-station which is usually a terminal station of the cable-traction route, and 1 is a 45 framework constituting part of the structure for supporting the terminal arrangements. To this frame are led the standing rope 2, which is ordinarily anchored, as shown, and the course of which is continued by the rail 50 3, and the traveling rope 4, which is carried

by suitable pulleys, one of which is shown at 5. The trolley 6 runs on the standing rope and has the hangers 7, by which the bucket 8 is suspended, as clearly shown in Figs. 1 and 3. Carried by the bucket-hangers is the grip 55 9, which in transit grasps and holds the traveling rope, but at a station is released, allowing the bucket to stop for loading or discharging. In Fig. 1 the grip has been released, and the bucket in that figure is supposed to be stationary. Secured to the bucket-hangers is a bracket 11, from which the grip-hanger 12 is suspended by a pivot 13, giving it a certain amount of freedom in the direction of travel. The grip-hanger has ears 14, in which 60 the grip-casing 15 is mounted by pivots or trunnions 16, Fig. 7, and the grip can swing on such pivots, so as to fully clear itself from the rope (see change of position dotted in Fig. 4) as well as to conform to the grooves in guide-sheaves while traveling. The grip-casing is 65 open at front and rear and closed at top and partly closed at the bottom and forms a receptacle as well as a guide for the grip-operating mechanism. The casing is enlarged toward the rear, Figs. 4 and 5, and the bottom is inclined, as shown at 17, to afford room for the operating-lever and its connections. One member of the grip proper is a stationary die 18, having a grooved face to partly encircle 70 the rope, and which is adjustably secured in place by screw-bolts 19, Fig. 6, which pass through lugs 21 of the casing. The other member of the grip is a jaw or strap 22, Fig. 9, which has a sliding movement upon the 75 bottom of the casing and is provided with an upwardly and backwardly turned front end having a slot 23. The upturned portion is rounded internally to coöperate with the die 18 in gripping the rope, Fig. 4, and is also 80 rounded or tapered externally to conform to the grooves in the rope-carrying pulleys when necessary. The bottom of the jaw has a slot 24 and is also cut away or recessed, as shown at 25, to allow other mechanism to be set in 85 position and to be operated. This jaw is secured to a slide 26 by a pin 20, and the slide has a downwardly-projecting wing 27, provided with the obtuse angular slot 28. The slide 26 and jaw 22 are operated by a lever 90 100.

29, whose bifurcated front end is pivoted upon a shaft 31 in the casing. This lever has a projecting pin 32, which when it is thrown up enters the slot 28, moves the slide 26 forward, and opens the jaw, as shown in Fig. 5. When the lever is thrown down, the pin 32 acts against the other wall of the slot and moves the slide and jaw to the closed position. (Shown in Fig. 4.) For securing and maintaining the grip additional mechanism is provided 10 operated by the lever 29. A hook-shaped link 36 is connected to the lever by a pin 37, the hook when the grip is closed engaging with the shaft 31 between the projecting pivoted ends of the lever, Figs. 4 and 6. To this link is pivoted at 30 the keeper 38, which passes through the bottom of the casing and through the recess 25 of the jaw. The keeper has hooks 39 41, which are adapted to engage, 15 respectively, with the slots 23 and 24 of the jaw, and has a short longitudinal movement limited by a pin 42, which is held in the lugs 21 of the casing and passes through an angular slot 43 in the keeper. A link 44 is pivoted to the keeper and to a boss 45 of the casing, which relieves the strain on pin 42 and also holds the keeper in the dead-line of resistance when the grip is closed. Assuming the grip to be closed, as shown in Fig. 4, the 20 keeper and its hook-shaped link are in line, with the keeper drawn rearwardly and holding the jaw rigidly and compressing the rope. When the lever is thrown up to the position of Fig. 5, the joint between the keeper and its hooked link is broken at their pivotal connection before the slide and jaw move forward, and the keeper is moved slightly upward and forward and out of engagement with the jaw. The slide then moves the jaw 25 forward and the rope is released.

Referring again to Figs. 1 and 2, I now describe the automatic operation of the grip at a station. When necessary to distinguish them, I shall designate the bucket of Fig. 1 as the "preceding" bucket and the portion 45 of the bucket, or rather of its hanger, shown at the left of Fig. 2 as the "following" bucket. Any bucket comes in with its grip closed and grip-lever down. The lever projecting sidewise strikes an upward incline 46 on the frame, which throws it up and opens the grip and which is continued as a horizontal rail 47 to keep the lever up and the grip open. As the grip is released from the traveling rope before the bucket reaches the loading-point, I provide means for bringing the bucket up to that point independently of the rope. The means I prefer to employ comprise a belt or chain mounted on loose sprocket-wheels 48. The chain 49 runs with the arrow in Fig. 10 and carries a series of projections 51. The shaft 52 has a pulley 53, from which a belt extends to a smaller pulley 54 on a shaft 55, which may be utilized as a driving-shaft 60 to receive power from any suitable source,

but has a special function hereinafter described. As the grip is opened on the incoming bucket one of the projections of chain 49 strikes a pin 57 on the bucket-hanger, Fig. 3, and so propels the bucket along to the loading-point, in which place Fig. 1 shows it. The grip-casing passes between two guides 58 70 59, Figs. 1, 3, and 7, which are deflected downwardly past the loading-point and then upwardly to their former level. This deflection 75 forces the front end of the grip downwardly (see dotted lines in Fig. 4) and clears it of the rope and from the path of any broken wires of the rope until the subsequent upward deflection brings the jaw into gripping position 80 again. As the bucket is traveling faster than the propelling-chain 49 until the grip has been released, I provide sprocket-shaft 52 with any simple form of clutch which will enable the chain to take the speed of the rope when it 85 first strikes the bucket. Such a clutch is shown at 61 in Fig. 2 as a simple ratchet-collar, pressed by a spring 62 into engagement with a corresponding ratchet on the adjacent loose sprocket-wheel 48. The ratchet allows 90 the sprocket to slip on the shaft at any speed imparted by the rope. When the grip has been released, the chain carries the bucket forward at the normal speed of the shaft 52. When the bucket has been loaded or discharged, it is moved ahead, and I have shown 95 means by which such movement is accomplished automatically by the incoming following bucket. The object is not only to move the preceding bucket, but to start it slowly 100 and without jar and to increase its speed, so that when it takes the rope its speed will be approximately that of the rope, thereby doing away with any jar at its connection. In Figs. 1 and 2 a slide 63 is movable in a guide-frame 64, which has a slot 65, curved upwardly at its forward end. The slide has a projection 66 extending through the slot, which is struck by a lug 67 on the bucket-hanger. Secured to the slide is a chain or rope 60, 110 which normally is led over a cam 68 on a circular disk 69 and thence around the periphery of said disk, to which it is made fast, as shown by dotted lines in Fig. 1. The cam and disk have grooved edges, as shown, 115 and constitute one structure, in which the periphery of the cam from a point near the center of such structure is formed on a lengthening curve, which finally merges into the periphery of the disk. The shaft 72, which carries disk 69, is provided with a belt-pulley 73 and also with a grooved pulley 74, from 120 which a counterweight 75 is suspended to form a means for automatically retracting the slide. From pulley 73 a twisted belt extends to a pulley on a shaft 76, which drives a sprocket-chain 77, substantially like chain 49. Either of shafts 72 76 may be provided with a ratchet or like clutch to permit the cam-disk 125 to move backward without moving the chain 130

77, which when in motion follows the arrow in Fig. 10. As the following bucket enters, the slide is moved and moves the sprocket-chain 77 with increasing rapidity as the radius of the rope 60 lengthens. This movement causes the chain to carry the preceding bucket forward with the grip still open. The upward deflection of rails 58 59 puts the grip in proper position relatively to the rope, and immediately after the pivoted and weighted incline 78 throws the grip-lever down and closes the jaws on the rope. This incline is pivoted in order that it may yield at a certain pressure. It should be stated that the lever itself may be weighted to assist in holding the grip closed and the rope under compression. While the chain 49 may be driven by external power, as stated, I have shown means by which the preceding bucket as the rope carries it from the loading-point sets such chain in motion. A third carrying-chain 79, constructed substantially like those described, is carried by sprockets 81 82. Sprocket 81 is on shaft 55, which has a pulley 54, belted to pulley 53 on shaft 52, as before described. When the bucket reaches chain 79, the grip is fully engaged, and hence the motion of the bucket is transmitted back to chain 49. Thus while the following bucket carries the preceding bucket away from the loading-point the preceding bucket reciprocally brings the following bucket up to such point.

I do not limit myself to the exact construction and arrangements herein described, and shown in the drawings, as I desire to avail myself of such modifications and equivalents as fall properly within the spirit of my invention.

Having thus fully described my invention, what I claim as new, and desire to secure by Letters Patent, is—

1. In a system of cable traction, the combination with the traveling rope, of a bucket, an opening and closing grip carried thereby, means for automatically opening the grip, means for automatically shifting the grip away from the rope, means for automatically returning the grip toward the rope, and means for automatically closing the grip upon the rope.

2. In a system of cable traction, the traveling rope, a bucket, an opening and closing grip pivoted to said bucket so as to be capable of swinging away from the rope and toward the rope, and means for automatically imparting such swinging movements to the grip.

3. In a system of cable traction, a supporting structure, a traveling rope entering the same, buckets having opening and closing grips, and adapted to be propelled by said rope, means carried by the structure for opening the grip of a bucket, and a movable carrier for continuing the movement of the released bucket to a predetermined position on said structure.

4. In a system of cable traction, a supporting structure, a traveling rope entering the same, buckets having opening and closing grips, and adapted to be propelled by said rope, means carried by the structure for opening the grip of a bucket, and an endless chain for continuing the movement of the released bucket to a predetermined position on said structure.

5. In a system of cable traction, a supporting structure, a traveling rope entering the structure, buckets having opening and closing grips and adapted to be propelled by said rope, means carried by said structure for opening the grips of the buckets, a carrier for propelling a released preceding bucket away from a predetermined position on said structure, and means operated by a following bucket for actuating said carrier.

6. In a system of cable traction, a supporting structure, a traveling rope entering the structure, buckets having opening and closing grips and adapted to be propelled by said rope, means carried by said structure for opening the grips of said buckets, a movable carrier for continuing the movement of an entering bucket to a predetermined position on the structure, a second carrier for continuing the movement of a preceding bucket from said predetermined position, and means operated by the entering bucket for operating said second carrier.

7. In a system of cable traction, a supporting structure, a traveling rope entering the same, buckets having releasable grips and propelled by said rope, means carried by the structure for releasing said grips and for clamping said grips, a carrier for moving a preceding released bucket from a predetermined position on said structure, and means including an accelerating device and operated by a following bucket for actuating said carrier.

8. In a system of cable transportation, a supporting structure, a traveling rope, a carrier for moving a bucket away from a stationary position on said structure, and movable means in the path of a following bucket and actuated thereby for starting said carrier and accelerating its motion.

9. In a cable-traction system, the combination with the traveling rope and with buckets releasable from and attachable thereto, of a carrier-chain for moving a released bucket away from a position of rest on said structure, a slide in the path of a following bucket and adapted to derive a limited movement therefrom, and connections between said slide and said carrier.

10. In a cable-traction system, the combination with the traveling rope and with buckets releasable from and attachable thereto, of a carrier-chain for moving a released bucket away from a position of rest on said structure, a slide in the path of a following bucket and adapted to derive a limited movement.

therefrom, and connections between said slide and said carrier, which connections include an accelerating device.

11. In a cable-traction system, the combination with the traveling rope, and with buckets releasable from and attachable thereto, of a carrier-chain for moving a released bucket away from a position of rest on said structure, a slide in the path of a following bucket and adapted to derive a limited movement therefrom, and connections between said slide and said carrier, which connections include a shaft, a circular disk thereon, a cam associated with said disk and having its periphery independent of that of the disk near the axis of rotation, but ultimately merging with the periphery of the disk, and a rope connecting said slide with said cam and disk.

12. In a cable-traction system, the combination with the traveling rope, and with buckets releasable from and attachable thereto, of a carrier-chain for moving a released bucket away from a position of rest on said structure, a slide in the path of a following bucket and adapted to derive a limited movement therefrom, connections between said slide and said carrier, and means for disengaging said slide from the bucket.

13. In a cable-traction system, the combination with a supporting structure, a traveling rope, and buckets propelled thereby, of opening and closing grips pivoted to said buckets, means for releasing and reengaging said grips, and guide-rails on the structure for swinging the released grips away from and toward the said rope.

14. In a cable-traction system, the combination with a supporting structure, a traveling rope, and buckets propelled thereby, of opening and closing grips pivoted to said buckets, means for releasing and reengaging said grips, and guide-rails on the structure having a depression and located in the path of the grips adapted by contact with said grips to swing them away from and toward the said rope.

15. In a system of cable traction, having a traveling rope and buckets provided with grips, means for automatically handling such buckets at a station, comprising three chain carriers and an accelerator, and involving two independent buckets in the following sequence of operation: the moving of the second carrier by the action of an incoming or following bucket upon the accelerator and the carrying of a preceding bucket from a place of rest by said second carrier; the driving of the third carrier by contact with the said moving

preceding bucket, and the bringing of said incoming or following bucket to the said place of rest by the movement of said first carrier derived from said third carrier.

16. In a cable-traction system, the combination with a supporting structure, the traveling rope and a bucket having a releasable grip and adapted to be propelled by said rope, of means for releasing the grip of each incoming bucket, a carrier for bringing said released bucket to a place of rest, a projection from the bucket adapted to strike said carrier, means for driving the carrier at a normal speed and a clutch included in the gearing of the carrier whereby said carrier can be impelled by the bucket, before the release of the latter, at a rate of speed greater than its normal speed derived from said driving means.

17. In a grip for the described purpose, the combination with a grip-casing of a stationary die, a sliding strap and adapted to coöperate with the stationary die, an operating-lever connected to said sliding strap and a movable keeper in the casing independently connected to said lever and adapted to engage said strap, and to release said strap to permit the said lever to operate the same.

18. In a grip for the described purpose, the combination with a grip-casing of a stationary die, a movable strap, a slide connected to the movable strap, a keeper having a hooked end for engaging a slot in said strap and having also a loose connection with the casing, and an operating-lever for actuating said slide in both directions and also for actuating the keeper.

19. In a grip for the described purpose, the combination with the grip-casing, of a stationary die, a sliding strap, an operating-lever, and a keeper connected to said lever and adapted to be engaged with and disengaged from said strap by movements of the lever.

20. In a grip for the purpose described, a casing having a stationary die, a sliding strap coöoperating therewith, a lever connected to said strap for moving it in both directions relatively to the die, and an independently movable keeper, separately connected to said lever, and adapted to be engaged with said strap on a dead-line of resistance through the pivot of the lever.

In testimony whereof I have affixed my signature, in presence of two witnesses, this 11th day of July, 1903.

ARTHUR PAINTER.
